UNITED STATES PATENT OFFICE.

SUSAN L. ARNOLD, OF OTTAWA, ILLINOIS, ASSIGNOR OF ONE-FOURTH TO MARY ELEANOR NOYES AND ONE-FOURTH TO GEORGE A. GUTTING.

DESIGN FOR A WATCH-FOB OR TOY.

48,848.

Specification for Design.

Patented Apr. 11, 1916.

Application filed September 19, 1912. Serial No. 721,333. Term of patent 7 years.

To all whom it may concern:

Be it known that I, SUSAN L. ARNOLD, a citizen of the United States, residing at Ottawa, in the county of La Salle and State of Illinois, have invented a new, original, and ornamental Design for a Watch-Fob or Toy; and I do hereby declare the following to be a full, clear, and exact description of the invention, such as will enable others skilled in the art to which it appertains to make and use the same.

This invention relates to a design for toys, watch fobs and other articles of personal ornament.

The invention consists of the ornamental

design as herein shown consisting of the representation of a moose holding a man's hat in his mouth.

I claim:—

The ornamental design for a watch fob or toy comprising a bull moose having a hat in its mouth, as shown and described.

In testimony whereof I have signed my name to this specification in the presence of two subscribing witnesses.

SUSAN L. ARNOLD.
